J. M. Simms

ATTORNEY

UNITED STATES PATENT OFFICE

GEORGE A. MUMFORD, OF ROCHESTER, NEW YORK

IRONING ROLL

Application filed June 13, 1928. Serial No. 285,151.

The present invention relates to cushions such as used in padded rolls and beds of ironing and pressing machines and other places where similar conditions exist. An object of this invention is to provide a construction in which the cushion has greater durability and will not mat. Another object of the invention is to provide a cushion which is so constructed as to provide a large space for the collection of vapor. Another object of the invention is to provide a cushioned surface formed of a plurality of rigid surface forming elements so mounted that no lateral strains are imposed upon the resilient means which supports them. A still further object of the invention is to provide a cushioned surface formed of a plurality of surface forming elements which are readily removable to permit the repair of the cushion. To these and other ends, the invention consists of certain parts and combinations of parts, all of which will be hereinafter described, the novel features being pointed out in the appended claims.

25 In the drawings:

Fig. 1 is a transverse section through a padded roll of an ironing machine embodying the present invention;

Fig. 2 is a sectional view through a fragmentary portion of the roll on the line 2—2, Fig. 1;

Fig. 3 is an enlarged sectional view through one of the guides and one of the surface forming elements; and

Fig. 4 is a view showing one of the elements partially in section and partially in side view arranged in one of the channels or guides, the resilient means also being shown in partial section and partial elevation.

In the illustrated embodiment of the invention, 1 illustrates a shaft having collars 2 thereon supporting a hollow cylinder 3 forming the support as a whole for the cushion. The cushion, in this instance, is formed by a plurality of surface-forming members 4 in the form of rigid plates provided with perforations 5 through which the vapor or steam may pass after passing through the covering pad 6, so as to keep the pad in a dry condition.

The members 4, in this instance, are ar-

ranged in parallel lines and guided against lateral movement on the supporting cylinder 3. To this end, the supporting cylinder is provided with a plurality of longitudinally extending guides. Each of these guides are of channel formation having a bottom wall 7 conforming to the cylinder 3 and secured by welding to the latter. From this bottom wall project two side walls 8 which have at their outer edges inwardly turned flanges 9 forming a restricted outlet for the channel and also acting as stops. Each channel has a plurality of surface forming members 4 guided therein, and arranged end to end. To this end, a web 11 is projected from the rear face of each elongated surface forming member 4 and is guided by the walls of the restricted outlet 10 of the channel. At the free end of this web two outwardly extending flanges 12 are provided which cooperate with the side walls 8 and the flanges 9. This cooperation between the flanges 12 and the side walls and also between the web 11 and the ends of the flanges 9 prevents any sidewise movement of the surface forming member 4 while permitting the latter to be depressed. The flanges 9 limit the outward movement of the surface forming members.

Resilient means is interposed between the surface forming members and the support 80 for said members. In this instance, this resilient means comprises a plurality of leaf springs 13 superimposed one upon the other and locked together by clips 14 having side arms 14^a fitting in notches 20 in the sides of the springs. These leaf springs form an arched spring means and the top of each arch abuts the bottom 7 of the channel or guide while the ends of the arch abut the flanges 12. To confine each set of springs to one surface forming member each of said surface forming members have projecting from it two stop lugs 15 adjacent opposite ends of each member and serving to confine a set of springs between them.

Removable heads 16 close the ends of the drum or cylinder 3 and extend beyond said cylinder substantially to the periphery of the roll as a whole. One of these heads is provided with ports 17 opening laterally be-

tween the channels and communicating at their inner ends with an annular chamber 18 which by ports 19 connects with a transverse port 20 in the shaft 1 the latter having a longitudinally extending port 21 which may be connected with an exhaust apparatus to permit the withdrawal of steam or vapor from the spaces between the channels. The springs are so enclosed that, with the exhaust apparatus connected to the roll, little or no moisture collects upon the springs and, in this way, the life of the springs is extended.

It is apparent that a button or other hard device passing between the padded roll and an ironing surface will cause one of the surface forming members to be pressed inwardly against a set of springs 13. Of course, the surface forming member will rock in the channeled guide, depending on which side of the center of the member is engaged by the hard device, and will return to its initial position after passing out of engagement with such device. Each surface forming member is removable or is held against lateral shifting so that no strain is imposed upon the springs or resilient devices which hold the surface forming members in normal positions. The devices may be readily removed from the channels by removing them longitudinally of the channels, causing the springs to travel with them. A large space is provided in which the vapor may collect and the springs are so mounted that only a small amount of the vapor can reach them.

It will be noted that longitudinally extending channels are provided from one end of the roll to the other and the vapor passing into and through these channels tends to maintain the cushioned surface in a heated condition and thus in a dry condition. At the same time the resilient or spring means which opposes the movement of the surface forming members is housed against the action of the vapor.

What I claim as my invention and desire to secure by Letters Patent is:

1. An ironing surface comprising a rotary support, a plurality of surface forming members, resilient means acting upon said surface forming members to hold them in normal positions, and guiding means between the rotary support and the surface forming members preventing sidewise movement of the surface forming members in the direction of turning of the rotary member.

2. An ironing surface comprising a rotary support, of a plurality of surface forming members each having a rigid web projected from the inner side thereof and extending longitudinally of the axis of rotation of the support, resilient means acting on said surface forming members to hold them in normal positions and means cooperating with opposite sides of said webs to guide the surface forming members on the support toward

and from the axis of rotation of the support.

3. An ironing surface comprising a rotary support, of a plurality of longitudinally extending channels arranged on the support in parallel relation to each other and to the axes of rotation of the support, a plurality of surface forming members guided in each of said channels and held against sidewise movement in the direction of turning of the rotary support, and resilient means arranged in the channels for holding the surface forming members in a normal position.

4. An ironing surface comprising a support, a plurality of surface forming members provided with openings and movably mounted on the support, resilient means opposing the movement of the members on the support, and means housing the resilient means and providing spaces through which vapor may be drawn from the openings in the surface forming members without contacting with the resilient means.

5. An ironing surface comprising a plurality of surface forming members formed with perforations and arranged in parallel rows, resilient means opposing the movement of said members, and means enclosing said resilient means and providing parallel channels through which vapor passing through the surface forming members may be drawn without contacting with the resilient means.

6. The combination with a channel member having a restricted outlet, of a surface forming member having a web projected from the inner side thereof and guided by the walls of the restricted outlet of the channel, means carried by said web for limiting the outward movement of the surface forming member, two abutments carried by the web within the channel, and bowed spring means having its end portions cooperating with the abutments and its bowed portion cooperating with the bottom of the channel member.

7. An ironing surface comprising a rotary support, a plurality of parallel channel members arranged longitudinally of said support to provide vapor spaces between them, a plurality of surface forming members guided in each channel, and resilient means opposing the movement of the surface forming members and arranged in said channels.

GEORGE A. MUMFORD.
